NOZZLE HEAD

Herbert S. Ruekberg, Highland Park, Ill.

Application October 20, 1950, Serial No. 191,255

3 Claims. (Cl. 299—107)

1

This invention relates in general to a "low-pressure" one piece spray nozzle for dispensing liquids from a flexible container and more specifically to a type thereof where a moving air column produced inside the container by applying external pressure against the outside walls of the container, is utilized to force the liquid through an orifice in the nozzle.

In dispensing a liquid in a finely divided spray from a closed container, where the liquid in the container is under a relatively low pressure, it has been necessary to atomize the liquid from the container by the use of an independent supply of air, usually by means of a flexible rubber bulb member, such as used in the conventional atomizer. In order to dispense a liquid from a closed container in a finely divided spray without the use of such an outside atomizer, it has been necessary to keep the liquid in the container under a relatively high pressure, or to use a highly volatile fluid in the container mixed with the liquid to be dispensed.

Thus, the advantage of having a nozzle which may be utilized to dispense liquid from a closed container in a finely divided spray under low pressure wherein the outside atomizing bulb is eliminated can readily be seen.

Accordingly, it is a primary object of this invention to provide a one piece nozzle for dispensing liquids under low pressure from a closed flexible container in a finely divided spray.

It is a further object of this invention to provide a nozzle for dispensing liquids from a closed flexible container under a low pressure, wherein, pressure exerted upon the outside walls of the container is utilized to force the liquid through an orifice in the nozzle.

Another object of this invention is to provide a one-piece nozzle made of any suitable material, such as vinyl resin in this particular embodiment, to carry out the aforesaid objects.

Another object of this invention is to provide a nozzle, as aforesaid, utilizing the air disposed within the container to atomize and expel the liquid therefrom.

A further object of this invention is to provide a nozzle, as aforesaid, which is simple in construction, inexpensive to manufacture and readily adapted to use with containers fabricated from a flexible and resilient material, such as vinyl resin or a similar plastic.

Other objects of this invention will become apparent to those familiar with this type of device by reading the following description and examining the accompanying drawing.

2

In the drawing:

Figure 1 is a cross-sectional view of my spray nozzle and a container in which it is mounted.

Figure 2 is an enlarged view in cross-section of the spray nozzle substantially as shown in Figure 1.

Figure 3 is a sectional view taken along the line III—III of Figure 2.

In meeting the above outlined objects, as well as others incidental thereto, I have provided a thimble shaped spray nozzle 10 (Figures 1 and 2) with a cylindrically shaped body portion 11 having a substantially closed end 12, said end 12 having an orifice 13 extending therethrough. A cylindrically shaped boss 14 is disposed within said body portion 11 integral with said end 12 and coaxial with said orifice 13. A liquid dispensing tube 15 is positioned within the cylindrical boss 14 in communication with said orifice 13. An air space is provided between the inner wall of the boss 14 and said tube 15, which also communicates with said orifice 13, and means are provided within the boss 14 to constrict the opening in said tube 15 when said tube is positioned within the boss 14 in communication with said orifice 13.

For the purpose of convenience, and without intending any limitations, the terms "inwardly" and "outwardly" used herein shall have reference to the geometric center of the nozzle 10 and parts thereof. The terms "upper" and "lower" shall be used in referring to the parts of the invention positioned, respectively, toward the upper and lower ends of the container 38 as shown in Figure 1.

The outer cylindrical body portion 11 (Figure 2) has a central, substantially cylindrical chamber 16 closed at the upper axial end thereof by the wall 12. The inside wall 17 of the chamber 16 is slightly tapered such as by 1 degree, so that it converges from the lower end thereof toward the wall 12. The outside surface 18 of the cylindrical portion 11 is preferably tapered inwardly from its upper end to its lower end, also at an angle of about 1 degree. A plurality of vertically disposed reinforcing members 19, 19a and 19b are positioned at equal intervals, as shown in Figure 3, along the inside wall 17 of the cylindrical body portion 11 and are integral therewith. The reinforcing members 19, 19a and 19b, which are partially cylindrical in shape and parallel to the central axis of the cylindrical body portion 11, are not essential to this invention and may, under some circumstances, be omitted.

The end wall 12 has a flange 20 integral there-

with and extending radially outwardly from said cylindrical portion 11. The orifice 13, which extends through the center of said end wall 12, is coaxial with the central chamber 16 of the body portion 11, and its inner wall 21 may be either cylindrical or slightly tapered, as required, with no appreciable variation in effect upon the performance of the nozzle. An annular ridge 23, integral with and extending upwardly from the upper surface 24 of the end wall 12, is coaxial therewith and disposed intermediate the outer circumference of said end wall 12 and said orifice 13.

The cylinder boss 14, which is disposed within the central chamber 16 and spaced radially inwardly from the inside wall 17 of said cylindrical body portion 11, is integral with and extends downwardly from the end wall 12, and has a substantially cylindrical opening 26 extending vertically therethrough. The central opening 26 communicates with the orifice 13 and is preferably coaxial both with the central chamber 16 and the orifice 13 (Figures 2 and 3).

A semi-circular boss 27 (Figures 2 and 3), having a radially inward straight edge or wall 25, is disposed within the upper end of said opening 26, integral with both the end wall 12 and a portion of the inner wall 28 of the inner cylindrical boss 14. This semi-circular boss extends from the sidewall 28 toward the orifice 13 so that its straight edge 25 is substantially tangent to the sidewall 21 of said orifice.

The semi-circular boss 27 extends downwardly from the end wall 12 a very small distance. In one preferred, illustrative embodiment for a nozzle having approximately a $\frac{1}{2}$ inch overall diameter, said distance is 0.013 inch.

The semi-cylindrical guide rib 29, which is integral with the inner wall 28 of the cylindrical boss 14, is positioned opposite said semi-circular boss 27 and its central axis is in a plane perpendicularly bisecting said straight edge 25 of the boss 27 (Figure 3). The rib 29 preferably extends the full length of the central opening 26 and is of such thickness, approximately $\frac{1}{4}$ of the diameter of said opening 26, that its innermost edge 30 is spaced only slightly outwardly from the wall 21 of said orifice 13. In said illustrative embodiment, this spacing is 0.006 inch.

A pair of semi-cylindrical guide ribs 29a and 29b, which are of considerably less thickness than said guide rib 29, are integral with the inner wall 28 of the cylindrical boss 14. Said guide ribs 29a and 29b are preferably positioned equidistant from said guide rib 29, and from each other, and preferably extend the full length of said opening 26. Said three ribs are so positioned with respect to each other that their inward extremities locate a theoretical circle eccentric to the orifice 13 and in this particular embodiment they are so positioned that said wall 25 coincides with a diameter of said theoretical circle. The exact size of the guide ribs 29, 29a and 29b and their positions will be described in more detail hereinafter.

A cylindrical fluid tube 15 (Figures 2 and 3), which has an outside diameter approximately equal to the distance between the inner edge 30 of the guide rib 29 and the diametrically opposite portion of the wall 28, has one end thereof snugly held within said opening 26 between the inner surfaces of said guide ribs 29, 29a and 29b (Figures 2 and 3). The upper end of said fluid tube 15 is disposed snugly against said semi-circular boss 27, which covers approximately one

half of the opening 35 in the fluid tube 15. The uncovered portion of said opening 35 communicates with the orifice 13 past the edge 25 of the semi-circular boss 27.

Although the relative sizes and positions of the guide ribs 29, 29a and 29b will be substantially as described herein, their exact sizes and positions will be dependent upon the inside and outside diameter of the tube 15, the size of the orifice 13, and the size of the semi-circular boss 27. The critical function of said guide ribs is to position said fluid tube 15 so that the semi-circular boss 27 will partially constrict the opening 35, where it communicates with said orifice 13, when the upper end of the tube 15 is bearing against the boss 27. The rib 29 has the additional function of spacing the tube 15 away from the sidewall 28 of the central opening 26 so that air passages 22 (Figure 3) are formed on either side of the rib 29, from the chamber 16 to the orifice 13.

It is to be understood that the exact size of the orifice 13 and the tube 15 can be varied to achieve the best results in dispensing different liquids, depending upon their vapor pressure and viscosity. In one particular preferred embodiment of the nozzle 10, the following dimensions have been found satisfactory: a central chamber 16 having a diameter of .42 inch; a cylindrical boss 14 having an outside diameter of .23 inch and an inside diameter of .15 inch; an end wall having an outside diameter of .531 inch; an orifice 13 having an exit opening of .031 inch and an entrance opening of .046 inch; a semi-circular boss 27 having a thickness of .013 inch and spaced outwardly from the central axis of said central opening 26 a distance of .023 inch; a guide rib 29 spaced outwardly from the central axis of said opening 26 a distance of .029 inch and guide ribs 29 and 29a extending into said opening 26 a distance of .016 inch.

Operation

Prior to operation, the container 38 (Figure 1) is partially filled with liquid to be dispensed and the nozzle 10, having the tube 15 positioned in the opening 26 therein, is inserted in the mouth of the bottle, the tube 15 being immersed in the liquid. The flange 20 on the end wall 12 rests against the lip 39 of the container mouth, and combines with the outside surface 18 of the nozzle 10 to provide a seal between said nozzle and said container.

In use, the liquid is dispensed from the container, by merely squeezing the sidewalls 40, whereupon said liquid is forced through the orifice 13 in a finely divided spray. The action which produces this spray will now be described. Compression of the sidewalls of the container 38 compresses the air in the chamber 41 between the liquid level and the spray nozzle. This compressed air urges the liquid in the bottle downwardly and then upwardly through the tube 15. At the same time, the compressed air in the chamber 41 escapes upwardly through the passages 22 in the opening 16 between the tube 15 and the wall 28 adjacent to the rib 29. Since the passages 22 communicate with the orifice 13, the compressed air rushes past the opening in the upper end of the tube 15, through which the liquid is emerging, and out through the orifice 13 carrying the liquid with it. The air rushing past the opening 35 in tube 15 reduces the pressure within said opening in the tube 15 according to the well known Venturi principle. This sudden

reduction in air pressure, combined with the constriction of the opening 35 in the tube 15 by the boss 27, effects a sudden expansion and atomization of the liquid just before it passes through the orifice 13.

The constriction to the flow of the liquid through the opening 35 of the tube 15 increases the velocity of the liquid flow and thereby assists in its atomization. The finely divided particles of liquid mix with the air rushing through the passages 22, to produce a finely divided spray. The spray is further divided by turbulence in the orifice 13, and by expansion as said spray escapes from said orifice.

When the air pressure in the container returns to normal, the liquid and air will cease flowing from the orifice 13. However, when the pressure on the sidewalls 40 of the container 38 is released, said walls will return to their normal positions. This produces a vacuum within the container whereby a fresh supply of air is drawn into the container through the orifice 13 and the passages 22 along the same paths through which the preceding charge was removed. At this point the container is ready for dispensing another charge of liquid.

It will be recognized that, although the above description is directed to a structure involving a vertical spray, the nozzle 10 may be inserted into a container having an appropriate opening in a sidewall thereof. Further, with only slight modification of the outer body portion 11 and no change in the remainder of the nozzle 10, said nozzle can be adapted for directing spray sideways from a conventional, vertical container.

Although the above mentioned drawing and description apply to one particular preferred embodiment of this invention, it is not my intention implied or otherwise, to eliminate other variations or modifications which do not depart from the scope of the invention unless specifically stated to the contrary in the hereinafter appended claims.

I claim:

1. In a spray nozzle, the combination comprising: a body member formed externally to engage a bottle mouth, said body member having a tube receiving central opening extending into one axial end thereof and an end member closing the opposite axial end thereof and having an orifice through said end member communicating with said tube opening; a semi-circular boss disposed at the bottom of said central opening ad-

jacent to said orifice, integral both with one sidewall of said central opening and with said end member, and partially defined by a plane substantially tangent to the edge of said orifice; a tube disposed within said central opening, having a diameter less than the inside diameter of said central opening; a plurality of spaced guide ribs disposed within said central opening integral with the sidewalls thereof and extending radially inwardly for positioning said tube with a part of its end snugly against said semi-circular boss for covering a part of the opening in said tube and with the uncovered portion of said opening communicating with said orifice.

2. In a spray nozzle head for association with a flexible bottle, the combination comprising: a body member formed externally to engage the mouth of said bottle, said body member being hollow and being open at one end and having an end member closing its other end; means defining an orifice in said end member; a cylindrical boss extending from said end member and positioned coaxially with said orifice, said boss being hollow and having a plurality of ribs extending inwardly from its inner wall, the respective inner extremities of said ribs locating a theoretical circle eccentric to said orifice; a semi-circular boss extending from said end member within said cylindrical boss and being partially defined by a wall tangent to the said orifice and constituting a diameter of said theoretical circle; whereby a tube received within said cylindrical boss may be positioned by said ribs co-axially with said theoretical circle and will be spaced from the adjacent end of said orifice a distance determined by the thickness of said semi-circular boss.

3. The device defined in claim 2 wherein two of said ribs are adjacent the ends of the wall defining the straight side of said semi-circular boss and the third rib is larger than said first two named ribs, lies in a plane perpendicularly bisecting said wall and is positioned on the other side of said orifice from it.
